CLAIM

The ornamental design for a reflector concentrator useful for solar energy, substantially as shown.

DESCRIPTION

FIG. 1 is a view in perspective of a reflector concentrator useful for solar energy according to my invention, and representing a view of what may form the front-/side, or rear/side, or vice versa, of such reflector collector, but which for ease of description will be designated as a front/side view.

FIG. 2 is a plan view of the reflector concentrator of FIG. 1.

FIG. 3 is an end elevation view of the reflector concentrator of FIG. 1, according to the illustrative convention adopted for FIG. 1.

FIGS. 4 and 5 are opposite side elevation views of the reflector concentrator of FIG. 1.
